AUTOMATIC RECLOSED CIRCUIT
BREAKER SYSTEM

Arvid E. Anderson, Drexel Hill, and Vernon L. Cox, Lansdowne, Pa., and Fred S. Wright, Kingsport, Tenn., assignors to General Electric Company, a corporation of New York

Application November 26, 1932, Serial No. 644,470

13 Claims. (Cl. 175—294)

Our invention relates to automatic reclosing circuit breaker systems and particularly to such systems in which the initial reclosure of the circuit breaker, upon the occurrence of an abnormal condition which effects the opening thereof, is effected as quickly as possible after the initial opening thereof and the subsequent reclosures, if any, are effected only after the circuit breaker has remained open for relatively long intervals of time. Such arrangements have been found desirable in practice in order to reduce to a minimum the length of time service is interrupted since most of the faults which cause a circuit breaker to open are of such a character that they cease to exist after the initial opening of the circuit breaker.

One object of our invention is to provide an improved automatic reclosing circuit breaker system of the above type and particularly a simple, inexpensive and pump-proof arrangement for effecting a single rapid or substantially instantaneous reclosure of the circuit breaker after the initial opening thereof.

Our invention will be better understood from the following description taken in connection with the accompanying drawing and its scope will be pointed out in the appended claims.

Referring to the accompanying drawing, Fig. 1 diagrammatically illustrates an automatic reclosing circuit breaker employing our invention and Figs. 2 and 3 illustrate modifications of portions of that system.

Referring to Fig. 1, 1 represents a suitable circuit breaker, examples of which are well known in the art, for connecting a supply circuit 2, which may be supplied from any suitable source, to a load circuit 3. As shown in the drawing, the circuit breaker 1 is of the well-known latched-in type and comprises a closing coil 4, which, when energized, closes the circuit breaker 1, a latch 5 for holding the circuit breaker in its closed position and a trip coil 6 which, when energized, releases the latch 5 and allows the circuit breaker to open. Although not essential the circuit breaker 1 is preferably of the trip-free type, examples of which are well known in the art, whereby the energization of the trip coil 6 while the closing coil 4 is still energized allows the circuit breaker to open and whereby the circuit breaker cannot be reclosed thereafter until the closing coil has been deenergized and subsequently reenergized. When a trip-free breaker is used a suitable latch-checking switch 55 is provided in order to prevent the breaker from

being reclosed until after the latch has been reset.

Any suitable fault responsive means, examples of which are well known in the art, may be provided for effecting the opening of the circuit breaker 1. As shown in the drawing, the fault responsive means includes three over-current relays 7, 8 and 9 which are respectively connected in series relation with different phases of the supply circuit 2. The relays 7, 8 and 9 are provided with contacts 10, 11 and 12 respectively which are connected in parallel with each other and in series with the trip coil 6 and the auxiliary contacts 13 on the circuit breaker 1 so that an energizing circuit for the trip coil 6 is completed to effect the opening of the circuit breaker when the current in any phase of the supply circuit 2 exceeds a predetermined value. While the relays 7, 8 and 9 may be either instantaneous or time delay closing, preferably they are of the quick reset type.

For effecting a single instantaneous reclosure of the circuit breaker 1 after the initial opening thereof in response to an abnormal load condition on the load circuit, we provide a control device 15 which, as shown in the drawing, comprises two electromagnets 16 and 17 and a latch 18 for maintaining the magnet 17 in its energized position, said latch 18 being arranged to be tripped by the magnet 16 when it is energized. Under normal operating conditions the magnet 17 is held in its energized position by the latch 18 and in that position the contacts 19 are closed and the contacts 20 and 21 are open. Also under normal operating conditions the magnet 16 is de-energized so that its contacts 22 and 23 are open.

The winding 24 of the magnet 16 is connected in series with the normally closed contacts 19 and the auxiliary contacts 25 on the circuit breaker 1 when it is open so that, as soon as the circuit breaker 1 opens, the magnet 16 is energized to close its contacts 22 and 23 and also to trip the latch 18 so that the contacts 19 are opened and the contacts 20 and 21 are closed. The closing of the contacts 23 completes a locking circuit for the winding 24 of the magnet 16 so that it remains energized, after the opening of the contacts 19, until the circuit breaker 1 closes and opens its auxiliary contacts 25. The closing of the contacts 22 and 20, which are connected in series, completes an energizing circuit for a control relay 26 which, in turn, completes an energizing circuit for the closing coil 4 of the circuit breaker 1. As soon as the circuit breaker 1 closes, the magnet 16 becomes deenergized and opens its

contacts 22 and 23. Since the contacts 19 are now open, the original energizing circuit for the winding 24 of the magnet 16 is open and, therefore, the magnet 16 cannot be energized again 5 until the winding 27 of the magnet 17 is energized to effect the closing of the contacts 19. Consequently, if the circuit breaker 1 should open immediately after its first reclosure, the circuit breaker is prevented from being reclosed in 10 spontaneously thereafter for a predetermined time. Suitable means are provided, as will be hereinafter described, for effecting the energization of the winding 27 of the magnet 17 if the circuit breaker 1 is closed at the expiration of a 15 predetermined time interval after a reclosure thereof.

In order to effect the reclosing of the circuit breaker 1 a predetermined number of times with relatively long predetermined time intervals between successive reclosures in case the circuit breaker does not remain closed after the initial instantaneous reclosure, and in order to limit the number of such time delayed reclosures, we provide a suitable motor-operated reclosing device 27', examples of which are well known in the art. As shown in the drawing, this reclosing device comprises a timer 28 and a substantially constant speed driving motor 29 therefor, which is permanently connected to a suitable source of current such as the supply circuit 2. The motor 29 is normally prevented from rotating by a stop 30 which engages a projection 31 on the timer 28. The stop 30 is arranged to be moved out of engagement with the projection 31 by a release magnet 32 when it is energized. The winding of the magnet 32 is connected in series with the contacts 21 of magnet 17 and contacts 33 of the control relay 26 so that when relay 26 is energized, to effect the initial reclosure of the circuit breaker 1, it also effects the energization of the release magnet 32 to start the reclosing device 27' into operation. In certain cases contacts 33 may be omitted from this circuit.

The timer 27' is provided with two sets of contacts 34 and 35 which are arranged to be closed successively, as the timer rotates with predetermined time intervals between successive closures thereof. The contacts 34 and 35 are also arranged so that only one set can be closed at any instant. When the contacts 34 are closed, a circuit is completed for a control relay 36 associated with the timer 28 if at the same time the circuit breaker 1 is open so that its auxiliary contacts 25 are closed. The relay 36, when energized, completed a locking circuit for itself so that the relay remains energized when the contacts 34 are subsequently opened. When the contacts 35 are closed and the relay 36 is also energized at the same time, a circuit is completed for the control relay 26 to establish an energizing circuit for the closing coil 4 of the circuit breaker 1.

After the timer 28 has been in operation for a predetermined time and the contacts 34 and 35 have been closed a predetermined number of times, the timer is arranged to interrupt the connection between contacts 39 and 40 and to establish a connection between contacts 39 and 41. If the circuit breaker 1 is closed at the time the contacts 39 and 41 are connected together, a circuit is completed for the winding 27 of the magnet 17 so as to restore it to its energized or normal position in which position it is held by the latch 18. If, however, the circuit breaker is open at the time the contacts 39 and 41 are connected together, the magnet 17 remains deenergized and no further

automatic reclosing of the circuit breaker can take place until after a suitable manual operation, such as the movement of the magnet 17 to its energized position, has been performed.

The operation of the arrangement shown in Fig. 1 is as follows: When the circuit breaker 1 is closed, it is held in its closed position by the latch 5 as long as conditions on the load circuit are normal. When an abnormal condition occurs which causes one of the overcurrent relays to close its contacts, a circuit is then completed through the auxiliary contacts 13 on the circuit breaker and the contacts of the operated overcurrent relay for the trip coil 6 to effect the opening of the circuit breaker 1. By opening its auxiliary contacts 13 the circuit breaker 1 interrupts the circuit of its trip coil 6 so that the spring 46' restores the latch 5 to a position in which it is operative to maintain the circuit breaker 1 in its closed position when it is subsequently reclosed. As soon as the circuit breaker opens, its auxiliary contacts 25 complete, through the contacts 19 of the magnet 17 and the contacts 39 and 40 of the timer 28, an energizing circuit for the winding 24 of the magnet 16. By closing its contacts 23, the magnet 16 completes independently of the contacts 19 a locking circuit for its winding 24 so that the magnet 16 is not deenergized by the subsequent opening of the latter contacts. The energization of the magnet 16 also trips the latch 18 so that the magnet 17 moves to its deenergized position and in so doing opens its contacts 19 and closes its contacts 20 and 21. As soon as the contacts 20 are closed, an energizing circuit is completed for the control relay 26 through the contacts 42 which check the position of latch 5, the contacts 22 of the energized magnet 16 and the contacts 39 and 40 of the timer 28. By closing its contacts 43, the control relay 26 completes a circuit for the closing coil 4 to close the circuit breaker 1. By closing its contacts 33 the control relay 26 also completes, through the contacts 21 of the magnet 17, an energizing circuit for the release magnet 32 of the reclosing device 27'.

When the circuit breaker 1 closes, the circuit of the winding 24 is interrupted at the auxiliary contacts 25 so that the magnet 16 becomes de-energized and opens its contacts 22 and 23. Since the magnet 17 is now in its deenergized position, the contacts 19 thereof are open so that, if the circuit breaker 1 should open immediately after its first reclosure, the magnet 16 is prevented from effecting another instantaneous reclosure.

As soon as release magnet 32 of the reclosing device 27' is energized, the timer 27' starts to rotate and after it has been in operation for a predetermined length of time, it closes the contacts 34. If at that time the circuit breaker 1 is open, a circuit is completed through the auxiliary contacts 25 on the circuit breaker, the winding of relay 36, contacts 34 and the contacts 39 and 40 to effect the energization of the relay 36. Relay 36 by closing its contacts 44 completes, independently of the contacts 34, a locking circuit for its operating winding so that the relay remains energized after the timer opens its contacts 34.

When the timer subsequently closes its contacts 35, a circuit is completed for the control relay 26. This circuit includes the contacts 42 on the latch 5, contacts 45 of the relay 36 and contacts 35, 44, 40 and 39 of the timer 27'. The control relay 26 then effects, in the manner above described, the energization of the closing coil 4 so as to close the circuit breaker 1. The control relay 26 also effects the energization of the release magnet 32

which, however, has no effect at this time because the timer is not in its normal position.

If following this reclosure the circuit breaker 1 should open immediately after it is closed, the timer 27', in the manner above described, effects another reclosure of the circuit breaker a predetermined time after the previous reclosure.

After the timer has successively closed and opened its contacts 34 and 35 a predetermined number of times, it disconnects contact 39 from contact 40 and then connects contact 39 to contact 41. If the circuit breaker 1 is closed at this time, a circuit is completed through the contacts 39 and 41 and the auxiliary contacts 46 on the circuit breaker 1 for the winding 27 of the magnet 17. The magnet 17 is then restored to its normal position in which position it is held by the latch 18.

The contacts 39 and 40 are disconnected from each other at this time by the timer 27' in order to prevent pumping of the circuit breaker 1 in case a permanent fault should occur while the contacts 39 and 41 are connected together. It is obvious that if a permanent fault should occur 25 while the contacts 39, 40 and 41 are all connected together, the circuit breaker 1 would be instantaneously reclosed in a manner above described after each opening thereof and would be open immediately after each reclosure. By having the contacts 40 disconnected from the contact 39, such pumping of the circuit breaker cannot occur because the circuit of the magnet 16 is opened while the closing circuit for the magnet 17 is completed.

35 After the contacts 39 and 41 have been connected together for a sufficient length of time to effect the restoration of the magnet 17 to its normal position, the timer 27' disconnects the contact 39 from the contact 41 and again connects the contact 39 to the contact 40. The timer then returns to its normal position where it is stopped by the projection 31 engaging the stop 30.

It will be noted that several important features are obtained by employing a control device of 45 the type shown in Fig. 1. If, for any reason, the circuit of the winding 24 should burn out or be interrupted or short-circuited, it is impossible to reclose the circuit breaker 1. Also the circuit breaker 1 cannot be closed if the latch 18 fails 50 to hold the magnet 17 in its energized position. Since it is necessary for the magnet 17 to be in its energized position before the magnet 16 can be energized and for the magnet 17 to be in its deenergized position while the magnet 16 is 55 in its energized position before the circuit breaker 1 can be reclosed, it will be observed that we have provided a very simple, reliable and fool-proof arrangement for effecting a single instantaneous reclosure of a circuit breaker.

60 In Fig. 2 we have illustrated a modified construction of the control device 15. Instead of having the contacts 19, 20 and 21 held in their normal position by the latch 18, they are held in their operating position by the latch 18 which is arranged to be tripped by the winding 27 when it is energized. The magnet 16, when energized, 65 is arranged to effect directly the opening of the contacts 19 and closing of the contacts 20 and 21. Since the windings and contacts of the control device shown in Fig. 2 are connected in exactly the same manner as the windings and contacts of the control device 15 shown in Fig. 1, further description of the device is deemed unnecessary.

75 In Fig. 3 we have shown a modification of the

timer 28 whereby the instantaneous reclosing control device 15 is rendered operative after any time delayed reclosure, in case the circuit breaker 1 remains closed after such a reclosure, instead of being rendered operative after a plurality of time delayed reclosures, as shown in Fig. 1. This result is obtained by designing the timer 28 so that a predetermined time after each completion of the circuit through the timer contacts 35, the timer contact 39 is disconnected from contact 40 and then is connected to contact 41 so that the circuit of the winding 27 of magnet 17 is completed to restore the control device 15 to its normal position in case the circuit breaker 1 is closed at the time the contacts 40 and 41 are connected together.

80 While we have, in accordance with the Patent Statutes, shown and described our invention as applied to a particular system and as embodying various devices diagrammatically indicated, changes and modifications will be obvious to those skilled in the art and we, therefore, aim in the appended claims to cover all such changes and modifications as fall within the true spirit and scope of our invention.

85 What we claim as new and desire to secure by Letters Patent of the United States, is:

1. In combination, an electric circuit, a circuit breaker in said circuit, and means for effecting an instantaneous reclosure of said circuit breaker after the initial opening thereof including a control device having a set of normally open contacts, a second set of normally open contacts, a set of normally closed contacts, means including an electromagnet for closing both of said sets of normally open contacts and for opening 100 said set of normally closed contacts when said electromagnet is energized and for opening one of said sets of normally open contacts only when said electromagnet is subsequently deenergized, means responsive to the initial opening of said circuit breaker for completing an energizing circuit 105 for said electromagnet through said normally closed contacts, and means responsive to the closing of both of said sets of normally open contacts for effecting the closing of said circuit breaker and the deenergization of said electromagnet.

110 2. In combination, an electric circuit, a circuit breaker in said circuit, and means for effecting

a single instantaneous reclosure of said circuit breaker after the initial opening thereof including a control device having a set of normally open contacts, a second set of normally open contacts, a set of normally closed contacts, means including an electromagnet for closing both of said sets of 125 normally open contacts and for opening said set of normally closed contacts when said electromagnet is energized and for opening one of said sets of normally open contacts only when said electromagnet is subsequently deenergized, means 130 responsive to the initial opening of said circuit breaker for completing an energizing circuit for said electromagnet through said normally closed contacts, means responsive to the energization of said electromagnet for completing a locking circuit 135 therefor which is independent of said normally closed contacts, and means responsive to the closing of both of said sets of normally open contacts for effecting the closing of said circuit breaker and the interruption of said locking circuit.

140 3. In combination, an electric circuit, a circuit breaker in said circuit, and means for effecting an instantaneous reclosure of said circuit breaker after the initial opening thereof including 145

- two electromagnets, means for normally maintaining one of said electromagnets in its energized position, means for effecting the energization of the other electromagnet in response to the opening of said circuit breaker only when said one of said electromagnets is in its energized position, means responsive to the energization of said other electromagnet for effecting the movement of said one of said electromagnets to its deenergized position and for effecting the closing of said circuit breaker, and means for subsequently restoring said one of said electromagnets to its energized position.
4. In combination, an electric circuit, a circuit breaker in said circuit, and means for effecting an instantaneous reclosure of said circuit breaker after the initial opening thereof including two electromagnets, means for normally maintaining one of said electromagnets in its energized position, means for effecting the energization of the other electromagnet in response to the opening of said circuit breaker only when said one of said electromagnets is in its energized position, means responsive to the energization of said other electromagnet for effecting the movement of said one of said electromagnets to its deenergized position, means for effecting the closing of said circuit breaker only when said one of said electromagnets is in its deenergized position and said other magnet is energized, means responsive to the closing of said circuit breaker for effecting the deenergization of said other electromagnet, and means for subsequently energizing said one of said electromagnets to restore it to its normal position.
5. In combination, an electric circuit, a circuit breaker in said circuit, and means for effecting an instantaneous reclosure of said circuit breaker after the initial opening thereof including two electromagnets, means for normally maintaining one of said electromagnets in its energized position, means for effecting the energization of the other electromagnet in response to the opening of said circuit breaker only when said one of said electromagnets is in its energized position, means responsive to the energization of said other electromagnet for effecting the movement of said one of said electromagnets to its deenergized position, means for effecting the closing of said circuit breaker only when said one of said electromagnets is in its deenergized position and said other magnet is energized, means responsive to the closing of said circuit breaker for effecting the deenergization of said other electromagnet, and timing means operative a predetermined time after the initial opening of said circuit breaker to effect the energization of said one of said electromagnets to restore it to its normal position and the interruption of the energizing circuit of said other electromagnets while said one of said electromagnets is energized.
6. In combination, an electric circuit, a circuit breaker in said circuit, means for effecting the opening of said circuit breaker, and means for effecting an instantaneous reclosure of said circuit breaker including normally closed contacts, latching means for maintaining said contacts closed, an electromagnet, means responsive to the opening of said circuit breaker for completing an energizing circuit for said electromagnet through said normally closed contacts, and means responsive to the energization of said electromagnet for effecting the operation of said latching means to allow said normally closed contacts to open and for effecting the closing of said circuit breaker.
7. In combination, an electric circuit, a circuit breaker in said circuit, means responsive to an abnormal condition on said circuit for effecting the opening of said circuit breaker, and means for effecting an instantaneous reclosure of said circuit breaker including normally closed contacts, latching means for maintaining said contacts closed, an electromagnet, means responsive to the opening of said circuit breaker for completing an energizing circuit for said electromagnet through said normally closed contacts, means responsive to the energization of said electromagnet for effecting the operation of said latching means to allow said normally closed contacts to open and for effecting the closing of said circuit breaker, and timing means controlled by the position of said circuit breaker for reclosing said normally closed contacts if said circuit breaker is in its closed position a predetermined time after the opening thereof.
8. In combination, an electric circuit, a circuit breaker in said circuit, and means for effecting a single instantaneous reclosure of said circuit breaker after the initial opening thereof including normally closed contacts and normally open contacts held in their normal positions by latching means, an electromagnet having normally open contacts, means responsive to the initial opening of said circuit breaker for completing a circuit for said electromagnet through said normally closed contacts, means responsive to the energization of said electromagnet for effecting the tripping of said latching means to effect the opening of said normally closed contacts and the closing of said first mentioned normally open contacts, and means responsive to the closing of both of said normally open contacts for effecting the closing of said circuit breaker and the deenergization of said electromagnet.
9. In combination, an electric circuit, a circuit breaker in said circuit, and means for effecting a single instantaneous reclosure of said circuit breaker after the initial opening thereof including normally closed contacts and normally open contacts held in their normal position by latching means, an electromagnet having normally open contacts, means responsive to the initial opening of said circuit breaker for completing a circuit for said electromagnet through said normally closed contacts, means responsive to the energization of said electromagnet for effecting the tripping of said latching means to effect the opening of said normally closed contacts and the closing of said first mentioned normally open contacts, means responsive to the closing of both of said normally open contacts for effecting the closing of said circuit breaker and the deenergization of said electromagnet.
10. In combination, an electric circuit, a circuit breaker in said circuit, and means for effecting an instantaneous reclosure of said circuit breaker after the initial opening thereof including a control device having a set of normally open contacts, a second set of normally open contacts, a set of normally closed contacts, means in-

- cluding an electromagnet for closing both of said sets of normally open contacts and for opening said set of normally closed contacts when said electromagnet is energized and for opening one 5 of said sets of normally open contacts only when said electromagnet is subsequently deenergized, means responsive to the initial opening of said circuit breaker for completing an energizing circuit for said electromagnet through said normally 10 closed contacts, means responsive to the closing of both of said sets of normally open contacts for effecting the closing of said circuit breaker and the deenergization of said electromagnet, and timing means for effecting subsequent reclosures 15 of said circuit breaker after relatively long predetermined time intervals and for effecting the restoration of said normally closed contacts and the other normally open contacts to their respective normal positions a predetermined time after 20 the initial opening of said circuit breaker.
11. In combination, an electric circuit, a circuit breaker in said circuit, latching means for maintaining said circuit breaker closed, means for releasing said latching means to effect the opening 25 of said circuit breaker, means operative after said circuit breaker opens for restoring said latching means to a position in which it is operative to maintain said circuit breaker in its closed position and means for effecting the reclosing of 30 said circuit breaker only when said latching means has been restored to said position.
12. In combination, an electric circuit, a circuit breaker in said circuit, latching means for maintaining said circuit breaker closed, means for releasing said latching means to effect the opening of said circuit breaker, means operative after said circuit breaker opens for restoring said latching means to a position in which it is operative to maintain said circuit breaker in its closed position a closing circuit for said circuit breaker, and means responsive to the opening of said circuit breaker for effecting the instantaneous completion of said closing circuit including contacts in said closing circuit closed by said latching means when in its restored position. 80
13. In combination, an electric circuit, a circuit breaker in said circuit, latching means for maintaining said circuit breaker closed, means for releasing said latching means to effect the opening of said circuit breaker, means operative after said circuit breaker opens for restoring said latching means to a position in which it is operative to maintain said circuit breaker in its closed position a closing circuit for said circuit breaker, and a latch checking contact associated with said circuit breaker and controlling said closing circuit so as to prevent the completion thereof until after said latching means has been restored to said position. 85
